UNITED STATES PATENT OFFICE.

JAKOB RANTASA, OF VIENNA, AUSTRIA-HUNGARY.

SLEIGH AND SLED.

No. 922,332.

Specification of Letters Patent.

Patented May 18, 1909.

Application filed January 9, 1908. Serial No. 409,959.

To all whom it may concern:

Be it known that I, JAKOB RANTASA, a subject of the Emperor of Austria-Hungary, residing at 8 Pramergasse IX, Vienna, Austria-Hungary, have invented certain new and useful Improvements in Sleighs and Sleds; and I do hereby declare that the following is a full, clear, and exact description of the same.

10 This invention relates to improvements in propelled sleighs and one of the objects of the invention is to provide an improved propelling means adapted to be adjusted by the operator to steer or guide the same.

15 A further object of the invention is the provision of an improved propeller provided with a plurality of blades or like members extending outwardly from a substantially continuous surface, which latter is so ar-

20 ranged as to engage the upper face of the snow and pack it so that engagement of the blades therewith will effectively advance the sleigh.

The invention will be more fully described 25 in connection with the accompanying drawing and will be more particularly pointed out and ascertained in and by the appended claims.

In the drawing:—Figure 1 is a view in side 30 elevation of a sleigh embodying the main features of my invention, showing a portion thereof in section on lines *b*—*b* of Fig. 2. Fig. 2 is a plan view with the body of the sleigh removed showing parts in section on 35 lines *a*—*a* of Fig. 1. Fig. 3, is a front elevation of the propelling means showing the manner of adjusting the same and a portion of the frame. Fig. 4 is a transverse sectional view of the propeller.

40 Like numerals of reference designate similar parts throughout the different figures of the drawing.

As shown in the drawing the sleigh consists of a frame having runners 28 and uprights 32 on which are mounted the frame members 31. A sleigh body is disposed upon the frame members 31 and may consist of a seat 30 and a motor hood 29. It will be understood however that the device of my 45 invention is not limited to that class of sleighs employing a prime mover.

The propeller, as shown, comprises a hub 14 provided with a polygonal bore from which radiates a plurality of braces 15. A 50 drum 16 is secured to said braces in concen-

tric relation with respect to said hub and a plurality of blades or propelling members 17 are secured to the periphery of said drum 16 preferably in alignment with said braces 15. Said blades 17 may be provided on their outer ends with spikes or propelling points 19, as shown. Segmental braces 18 are secured to said blades to stiffen the outer ends of the same and form a rigid structure. The drum 16 presents a substantially continuous 60 surface to the top of the snow and is adapted to be so disposed as to compress the snow when it travels over the same. Such compression of the snow will serve to pack the same between the lowermost or acting 65 blades so as to render the same highly effective in advancing the sleigh.

I will next describe the manner in which the propeller is mounted upon the blades.

As illustrated a shaft 1 is provided and the same is preferably polygonal in cross section and is adapted to fit the bore of the hub 14 with a free working clearance so as to permit the propeller to slide longitudinally on the shaft 1 and prevent it from rotating thereon. 75 Means are provided for adjusting the propeller longitudinally of the shaft and as shown said means consists of the following parts. A cross member 33 is slotted at 23 and a rack 22 is slidably mounted on said member 33 by means of bolts 34. Arms 21 are secured to said bolts 34 and have forked extremities engaging suitably formed grooves disposed at the end of the hub 14. A pinion 24 meshes with the rack 22 and is provided 80 with a pulley 35 about which a cord or wire 36 is trained. This cord 36 extends forwardly about a pulley 37 provided with teeth 38 which mesh with a pinion 39 mounted on the end of a steering post 25'. The usual 85 steering wheel 25 is disposed on the upper end of said post.

It will be readily seen from the foregoing that when the steering wheel 25 is rotated in either direction the propeller will be moved laterally on the shaft 1 thereby serving to change the course or direction of travel of the sleigh in accordance with extent of movement of the propeller from a central position.

As shown the propeller is driven from a 105 prime mover 40 through belts or cords 41 and 42, the latter operating a shaft 43. The shaft 43 is provided with chains or pulleys 44 connected by cords 45 with pins or pulleys 27, the latter being mounted on shaft 1. 110

It will be understood however that I do not wish to be limited to this particular method of driving the propeller.

In those embodiments of my invention where a propeller as shown in Fig. 4 is used in connection with a sleigh which may be guided by lateral movement of the propeller, it is desirable to adjust the propeller up and down in accordance with the depth of the snow on which the sleigh is traveling. If the snow is of considerable depth the drum 16 will tend to pack the snow too tightly and ride upon the snow thereby lifting the runners 28, in which case it will be desirable to adjust the propeller upwardly. On the other hand if the snow were not very deep it would be necessary to adjust the propeller downwardly in order that the ends of the points 19 could intersect the plane of the lower face of the runners and engage the road surface. Furthermore it is desirable to yieldingly mount the propeller so that in case the variation of the depth of the snow changes rapidly from one extreme to the other the propeller will automatically adjust itself to the condition thereby insuring the most efficient operation.

As shown guide-housings 3 are disposed between the runners 28 and the frame members 31 and are braced between the uprights 32 by struts 5. Said guide-housings are slotted on their inner walls as shown at 4 to permit the end of the shaft 1 to project thereinto. Split bearings 2 are guided in said housing 3 and receive the ends of the shaft 1. Springs 13 are interposed between the bearings 2 and spring plates 6 and bolts 6' pass through the plates 6 and the bearings 2 to enable the springs 13 to be placed under the desired tension. Sleeves 8, secured to the spring plates 6, extend upwardly through guides 46 and are journaled in the hub 12 of brackets 47. Said sleeves 8 are internally threaded. Operating threaded spindles 9 engage the interior thread of the sleeves 8 and carry on their upper ends pulleys 48. A cord or the like is trained about pulleys 48 and extends forwardly about a pulley 49 which latter is adapted to be operated by a hand-wheel 10.

It will be seen from the foregoing construction that by rotating the spindles 9 the sleeves 8 will be either raised or lowered, in accordance with the direction of rotation of the spindles 9, and the sleeves 8 acting through the bolts 6' will raise or lower the shaft 1. In raising the shaft 1 the parts will act through the bolts 6' as a rigid connection but when the shaft is lowered the springs 13 will yield if necessary. The springs 13 will permit the propeller to raise above its normally adjusted position so that the propeller will not have an excessive packed action on the snow and thereby retard propulsion of the sleigh. It will be understood that it is

desirable for the drum 16 to engage and pack the snow to a certain extent so that the blades 17 will effectively advance the sleigh and it will be also understood that where the snow is of considerable depth, with respect to the adjustment of the propeller, the propelling action will be somewhat retarded if the propeller could not yield upwardly so as not to exercise an excessive packing action.

If desired a brake 49 operated by a lever 75 may be provided.

I claim:—

1. A sleigh comprising in combination, a frame provided with runners, a shaft mounted in said frame, a propeller blade wheel provided with a snow engaging drum mounted on said shaft, and means for adjusting said propeller on said shaft to steer the sleigh.

2. A sleigh comprising in combination, a frame provided with runners, a propeller shaft, yielding bearings for said shaft, means for rotating said shaft, a propeller wheel mounted on said shaft, and means for adjusting said wheel laterally on said shaft to steer the sleigh.

3. A sleigh comprising in combination, a frame provided with runners, a shaft, adjustable yielding bearings on said frame carrying said shaft and displaceable vertically, propeller wheels mounted on said shaft, and means for displacing said propeller on said shaft to steer the sleigh.

4. A sleigh comprising in combination, a frame provided with runners, a shaft, a propeller wheel mounted on said shaft, means for adjusting said propeller laterally on said shaft to steer the sleigh, yielding bearings mounted on said frame and carrying said shaft, means for varying the yielding action of said bearings, and means for raising and lowering the bearings.

5. A sleigh comprising in combination, a frame provided with runners, a shaft, a propeller mounted on said shaft, means for adjusting said propeller on said shaft to steer the sleigh, adjustable yielding bearings on said frame movable vertically, rotary means for raising and lowering said bearings, and means for rotating said shaft.

6. A sleigh comprising in combination, a frame provided with runners, a shaft, a propeller wheel mounted on said shaft, yielding bearings carrying said shaft, a threaded sleeve connected with each of said bearings, a threaded spindle engaging each sleeve, means for operating said spindles in unison, and means for rotating said shaft.

7. A sleigh comprising in combination, a frame provided with runners, a shaft, a propeller wheel movable longitudinally on said shaft, yielding bearings carrying said shaft and movable vertically during rotation thereof, means adjusting said wheel on said shaft to steer the sleigh, and means for rotating said shaft.

8. A sleigh comprising in combination, a frame provided with runners, a shaft, a propeller wheel mounted on said shaft and consisting of blades provided with points or spikes, segments connecting said blades, a drum on which said blades are mounted, a hub supporting said drum, yielding bearings for said shaft, means for varying the yielding action of said bearings, said bearings being 5 displaceable vertically during rotation of said shaft, means for raising and lowering said bearings, and means for rotating said shaft.
9. A sleigh comprising in combination, a frame provided with runners, a plurality of radially projecting blades spaced apart from each other and adapted to project into the snow a relatively considerable distance, and a drum supporting said blades and presenting a continuous surface to the surface of the 10 snow and serving to pack the snow about the acting blades.
10. A sleigh comprising in combination, a propeller composed of a plurality of blades spaced apart from each other and adapted to 15 project a considerable distance into the 20 snow, said blades being provided on their outer ends with propelling points or spikes, a drum supporting said blades and presenting a continuous surface to the surface of the 25 snow and serving to pack the snow about the acting blades.
11. A sleigh comprising in combination, a frame provided with runners, a propeller mounted in said frame and comprising a hub provided with radially disposed braces, a drum mounted on said braces and presenting a substantially continuous face to the surface of the snow and disposed at a relatively 30 considerable distance above the bottom of said runners, blades projecting radially from said drum and spaced apart thereon and provided with propelling spikes or points, and segmental braces connecting said blades.

In testimony whereof I affix my signature 35 in presence of two witnesses.

JAKOB RANTASA.
